UNITED STATES PATENT OFFICE

171,694

SMOKER'S PIPE

Jerome Gevirmen, Brooklyn, N. Y.

Application August 18, 1953, Serial No. 26,495

Term of patent 14 years

(Cl. D85—8)

To all whom it may concern:

Be it known that I, Jerome Gevirmen, a citizen of the United States, residing in Brooklyn, county of Kings and State of New York, have invented a new, original, and ornamental Design for a Smoker's Pipe, of which the following is a specification, reference being had to the accompanying drawing, forming part thereof:

Fig. 1 is a top plan view of a smoker's pipe, showing my new design;

Fig. 2 is a side elevational view thereof; and

Fig. 3 is an end elevational view thereof.

I claim:

The ornamental design for a smoker's pipe, as shown.

JEROME GEVIRMAN.
